CLAIM

I claim the ornamental design for an analyte test meter, as shown and described.

DESCRIPTION

FIG. 1 is a perspective view of the analyte test meter, as seen from the front;

FIG. 2 is a top plan view thereof;

FIG. 3 is a first side elevational view thereof;

FIG. 4 is bottom plan view thereof;

FIG. 5 is a second side elevational view thereof;

FIG. 6 is a a front elevational view thereof; and,

FIG. 7 is a a rear elevational view thereof.

1 Claim, 3 Drawing Sheets**FIG. 1**

FIG. 2***FIG. 3******FIG. 6***

FIG. 4***FIG. 5******FIG. 7***
